UNITED STATES PATENT OFFICE.

SYLVANUS A. REED, OF NEW YORK, N. Y., ASSIGNOR TO THE REED PROPELLER CO. INC., OF NEW YORK, N. Y., A CORPORATION OF NEW YORK.

AERONAUTICAL PROPELLER.

Continuation of application Serial No. 570,139, filed June 22, 1922. This application filed May 12, 1924, Serial No. 712,644, and in France May 31, 1923.

This invention relates generally to aeronautical propellers and more particularly to propellers having multiple separable blades.

In my U. S. Letters Patent No. 1,463,556, granted July 31, 1923, and No. 1,518,410, granted Dec. 9, 1924, I have described and claimed certain types of my propeller including those having thin and sharp blades, preferably made of light weight metal of high tensile strength and forged, and with cross-sections adjusted to steadiness of pitch without excessive aggregate weight, and the propeller being made preferably in a single piece, although I also described and illustrated a propeller with separable blades united at the hub or shaft. My present invention refers to multiple blade construction in which I use separate blades united with each other at the hub or shaft, the means of blade junction being applicable not only to two blade propellers, but also to three blades, four blades or any desired number.

There are advantages of fabrication in the separate blade propellers, mainly concerned in the greater ease and economy of forging, but also in the assembly of three, four and other numbers of blades into a unit. Previous ways of connecting separate blades to a central drive-shaft applied to propellers and rotary fans or blowers, unite the blades to a central hub which is interposed between the blades. In my invention, I unite the blades to each other direct and use a central hub, boss or shaft attachment only to transmit torque and thrust, and having no share in supporting the radial tension due to centrifugal force. In the operation of aeronautical propellers, the rates of rotation and the propeller diameters and weights are such that centrifugal force is far the largest stress which the central portion has to sustain, and in my novel plan of uniting the separate blades direct to each other thus relieves the shaft-attaching means from the principal working stress. In my preferred form of central blade junction my novel method of blade construction also leaves the root portions of the blades at the proper angles for the pitch, and dispenses with a central reversing twist or series of bends, which is necessary in single-piece propellers of this type, when made interchangeable with the usual wood propellers on the same steel hub. My preferred form also accommodates con-

veniently, a pair of filler blocks or bosses 55 supplying the central hole and the fore and aft flat circular surfaces and bolt-holes adapted for attachment of the steel hubs in general use, and these bosses when finally bolted within the assembled blades are then 60 adapted to be mounted on an ordinary metal hub, not herein shown.

Other features of the invention will be hereinafter referred to.

In the drawings, in which a number of 65 embodiments of the invention have been selected for illustration:

Fig. 1, is an edge view of a form of propeller embodying my invention.

Fig. 2, is a view in cross-section of the 70 propeller shown in Fig. 1.

Fig. 3, is a face view of a propeller embodying another form of the invention.

Fig. 4, is a face view of one of the detached propeller blades shown in Fig. 3. 75

Fig. 5, is a view of one of the detached blades shown in Fig. 4, showing the other side and edge thereof.

Figs. 6 and 7, show inside and outside 80 views, respectively, of the pair of filler-blocks or members used at the central blade-junction. Fig. 8, shows a modification.

Referring to the drawings for a more detailed description of the invention, in the form shown in Figs. 1 and 2, the blade fork-prongs 19 and 20, and 21 and 22, of the respective blades 10 and 11, are elongated and have their outer ends bent into hooks substantially at right-angles to the prongs, and these hooks are placed in inter-locking arrangement in direct contact and are bolted together by bolts 23. The space between the prongs provides the central opening 24, for the reception of the drive shaft or hub, the forks straddling such part as in the other 95 form, the shaft being indicated at 18^a, Fig. 2. As the blades at their inner parts are deformed, filler blocks 25 and 26, are employed upon the opposite sides to accommodate such deformation. By the use of slots 27, in the 100 hooked ends of the blades, for the passage of the bolts 23, I am enabled to adjust the blades to change their pitch if desired.

In Figs. 3 to 7, I show a three-blade construction of propeller having separate blades 105 30, 31 and 32, each with its inner end forked so as to provide the interlocking prongs 33 and 34, which are made in hook form with

the beak of the hooks lying upon opposite sides of the blade. These hooks are set at different blade-positioning angles and considering the blade 30, and noting that the 5 blades are arranged at a third of a circle apart, its hook 34 is interlocked with the adjacent hook on blade 31, while its other hook 33, is interengaged with the adjacent hook on blade 32, and the remaining hook 10 on each of the blades 31 and 32, engage each other, as will be understood from Fig. 3. Bolts 35 are passed through each pair of the interengaging hooks, and the structure thus made a unit comprising the blades and 15 bolts. The notches between the prongs 33 and 34, provide the desired central opening 36, through which the hub or shaft is passed, and which part is spanned or straddled by the notched inner ends of the blades. The 20 hooks are bent to an acute angle to the blade and the lines of the bends form obtuse angles with the edges of the blade beyond the bends. These blade-positioning angles are calculated so that when the three blades are 25 interlocked the faces of the forks will lie together in coincidence and the inclination of the blades to the plane of rotation will be at the particular angle desired for the particular blade pitch designed. In this 30 union of the three blades, it will be seen that the forked prolongation of the leading edge of each blade interengages with the forked prolongation of the trailing edge of the adjacent blade.

35 Each of the hooks of the blades may be provided with slots 37, for the passage of the binding bolts 35, so that by loosening the bolts each blade may be adjusted on its longitudinal axis so as to change the pitch, 40 if desired, the bolts being then tightened to retain the adjustment.

In Figs. 6 and 7, are shown a pair of 45 filler members or blocks 38 and 39, which are applied to the opposite sides of the central junction of the blades, the one having its contacting face provided with projections 40 and the other having its contacting face provided with similar projections, which are shaped to conform to the inclined 50 blade parts at the central junction where they are interhooked with each other. The exterior faces of the respective blocks are flat and circular, and each block is formed with a central perforation 42, which registers with the central opening 36, of the assembled blades. A series of bolt holes 43, formed longitudinally through each of 55 said blocks are in alinement with each other and register with bolt-holes 44, formed at the inner ends of the respective blades, and when bolts are passed through these several 60 holes and secured with nuts, the filler blocks are securely clamped against the opposite sides of the inter-engaging blades and adapted to be mounted on an ordinary steel-hub,

not herein shown. The filler blocks are made of aluminum or any suitable light weight material which will serve the purpose of providing strong clamping means adapted for mounting the ordinary steel 70 hubs.

While the filler blocks shown in Figs. 6 and 7, are formed for co-operation with a three-blade construction as shown in Fig. 3, blocks 44 and 45, for a two-blade construction may be employed, as shown in Fig. 8, 75 and these blocks may be modified to accommodate any other desired number of inter-engaging separable blades. The two blades 10^a and 11^a shown in Fig. 8, have the fork-prongs at their inner ends made into overlapping hooks 46 and 47, which may be formed with slots 48 and 49, respectively, through which bolt 50 passes, and by means of which the parts are secured together in 80 adjustable relation which permits of each blade being turned slightly on its longitudinal axis to alter the pitch-angle thereof. These adjusting slots may be made either in one or both of the blade fork-prongs as 85 desired. In the event that the blades are designed for adjustment of the position thereof, the filler blocks 38 and 39 are mounted to provide spaces between the 90 blades and adjacent faces of the blocks, any such spaces that are left when the adjustment is made being filled with thin shim pieces, wedges, or the like which may be used as needed to fill in new spaces formed 95 when the blade angles are changed. When the spaces have thus been filled the bolts passing through the parts are tightened thereby 100 clamping the hub pieces tightly together.

In the constructions shown, the central 105 united formation is adapted for mounting on the conventional steel hub for wooden propellers and which have a shaft-embracing sleeve and two flanges and the two and three blade units described may 110 therefore be inter-changeable with conventional wooden propellers on the same steel hub.

This application in respect to the construction shown in Figs. 1 and 2, is a continuation of my said Patent No. 1,518,410 granted Dec. 9, 1924. The construction and formation of the respective blades herein shown and their pitch-angles may be carried out in 115 accordance with my said patents.

I wish to be understood as not limiting my invention to the particular forms of construction herein shown, as it is evident that various modifications may be made in the several parts thereof, without, however, departing from the spirit of my invention.

In cases where the slots and bolts are employed to alter the pitch-angles of the separate blades, the bolt holes of the filler blocks and also blades require a slight adjustment 130

to provide for the changed angle, or interchangeable filler-blocks may be used. In making my separable blade propeller, I find that excellent results are obtained by using 5 light-weight metal alloys, particularly aluminum alloys, such for example, as duralumin.

What I claim is:—

1. An aeronautical propeller having separable blades capable of being adjusted angularly on their longitudinal axes, said blades having forked root portions whereby the fork prong portions may be placed in straddled relation to a propeller shaft and 10 in overlapping adjustable relation to each other, and means for attaching the overlapping prong portions together and permitting the angular adjustment of said blades on their longitudinal axes.
2. An aeronautical propeller having separable blades displaceable around their longitudinal axes and provided with hook members at their root portions, said hook members being formed to be placed in interengaging relation to hold the blades in 15 operating position, and means carried by said hook-members for permitting displacement of said blades around their longitudinal axes.
3. An aeronautical propeller having separable blades capable of being adjusted angularly on their longitudinal axes and provided with laterally extending hook members at the blade root portions, the hook members of one blade being formed to be placed in interengaging relation with the hook members of another blade, and adjustable means for fastening the interengaged hook members together, said means being 20 mounted on said hook members and operating to permit the angular adjustment of said blades on their longitudinal axes.
4. An aeronautical propeller having separable blades capable of being adjusted angularly on their longitudinal axes and provided with forked prong root portions whereby the fork prong members may be placed in straddled relation to a propeller shaft, and the prong members on each blade 25 being bent laterally in opposite directions whereby the prong members of one blade may be placed in adjustable interengaging relation with the prong members of another, and means mounted on said hook prong members for permitting the angular adjustment of said blades on their longitudinal axes.
5. An aeronautical propeller having separable blades displaceable around their longitudinal axes and provided with forked prong root portions whereby the fork prong members may be placed in straddled relation to a propeller shaft, and the prong members on each blade being bent laterally 30 in opposite directions whereby the prong
6. An aeronautical propeller having blades angularly adjustable on their longitudinal axes and directly and rigidly connected together at their bases which connection sustains the entire stress of centrifugal force, and shaft attaching means to transmit torque and thrust, each blade of which propeller has two base terminal forked elongations bent in opposite directions overlapping and 35 interengaging with the adjacent corresponding blade elongations at a desired pitch angle, the interengaging portions provided with means to maintain them rigidly in position, and operating to permit the angular 40 adjustment of said blades on their longitudinal axes.
7. An aeronautical propeller having blades directly and rigidly connected together at their bases which connection sustains the entire stress of centrifugal force, and shaft attaching means to transmit torque and thrust, each blade of which propeller has two base terminal forked elongations bent in opposite directions overlapping and interengaging with the adjacent corresponding blade elongations at a desired pitch angle, and 45 filler pieces fitting one on the forward and the other on the rearward side of the assembled blades at the center of the propeller, said filler pieces having faces and bolt holes formed for attachment to forward and rearward hub flanges.
8. An aeronautical propeller having separable blades formed at their inner ends with integral extensions directly interengaging each other, said extensions being disposed at 50 certain blade-positioning angles.
9. An aeronautical propeller provided with separate blades capable of being adjusted angularly on their longitudinal axes and having their inner ends or root portions provided with prongs constructed and arranged so that when the blades are assembled the space between said prongs provides 55 a passage for a driving member, and said prongs of one blade overlapping those of another, one upon one side of the blade and one upon the other, and means for securing the parts together in adjustable relation, said 60 means being carried by said prongs.
10. An aeronautical propeller having separable blades provided at their inner ends with interengaging hooked parts having bolt-receiving slots, and bolts arranged in 65 said slots, whereby the pitch-angles of the blades may be changed.
11. An aeronautical propeller having separate blades and having their root portions provided with prongs projecting outwardly 70

members of one blade may be placed in adjustable interengaging relation with the prong members of another, and means mounted on said prong members for permitting displacement of said blades around 75 their longitudinal axes.

75

6. An aeronautical propeller having blades angularly adjustable on their longitudinal axes and directly and rigidly connected together at their bases which connection sustains the entire stress of centrifugal force, and shaft attaching means to transmit torque and thrust, each blade of which propeller has two base terminal forked elongations bent in opposite directions overlapping and 80 interengaging with the adjacent corresponding blade elongations at a desired pitch angle, the interengaging portions provided with means to maintain them rigidly in position, and operating to permit the angular 85 adjustment of said blades on their longitudinal axes.

80

7. An aeronautical propeller having blades directly and rigidly connected together at their bases which connection sustains the entire stress of centrifugal force, and shaft attaching means to transmit torque and thrust, each blade of which propeller has two base terminal forked elongations bent in opposite directions overlapping and interengaging with the adjacent corresponding blade elongations at a desired pitch angle, and 85 filler pieces fitting one on the forward and the other on the rearward side of the assembled blades at the center of the propeller, said filler pieces having faces and bolt holes formed for attachment to forward and rearward hub flanges.

90

8. An aeronautical propeller having separable blades formed at their inner ends with integral extensions directly interengaging each other, said extensions being disposed at certain blade-positioning angles.

95

9. An aeronautical propeller provided with separate blades capable of being adjusted angularly on their longitudinal axes and having their inner ends or root portions provided with prongs constructed and arranged so that when the blades are assembled the space between said prongs provides 100 a passage for a driving member, and said prongs of one blade overlapping those of another, one upon one side of the blade and one upon the other, and means for securing the parts together in adjustable relation, said 105 means being carried by said prongs.

110

10. An aeronautical propeller having separable blades provided at their inner ends with interengaging hooked parts having bolt-receiving slots, and bolts arranged in 115 said slots, whereby the pitch-angles of the blades may be changed.

115

11. An aeronautical propeller having separate blades and having their root portions provided with prongs projecting outwardly 120

at interengaging acute angles for positioning the blades when assembled, the prongs of one blade being formed to be placed in interengaging relation with the prongs of another 5 blade.

12. An aeronautical propeller having separate blades provided with pronged root por-

tions, said prongs projecting outwardly at interengaging acute angles, the engaging face of each prong disposed on a plane oblique 10 to the median plane of its blade.

In testimony whereof, I have hereunto set my hand.

SYLVANUS A. REED.
